UNITED STATES PATENT OFFICE.

JOHN M. HOLMES, OF GLENS FALLS, NEW YORK.

BARREL-COVER.

SPECIFICATION forming part of Letters Patent No. 634,729, dated October 10, 1899.

Application filed October 12, 1898. Serial No. 693,281. (No model.)

To all whom it may concern:

Be it known that I, JOHN M. HOLMES, a citizen of the United States, and a resident of Glens Falls, county of Warren, and State of New York, have invented certain new and useful Improvements in Barrel-Covers, of which the following is a specification, reference being had to the accompanying drawings, forming a part thereof, in which similar letters and figures of reference indicate corresponding parts.

This invention relates to improvements in barrel-covers, the object thereof being to provide an efficient device for temporarily covering the barrel after its head is removed, whereby the barrel is maintained in a closed condition to protect its contents. The device is so constructed that when attached to the barrel the same may be readily opened and closed for the purpose of removing a portion of the contents thereof at intervals, and it can be readily transferred from an empty to a full barrel as often as desired because of its durability and structural simplicity.

The invention will be hereinafter fully described, and specifically set forth in the annexed claims.

In the accompanying drawings, forming part of this specification, Figure 1 is a perspective view of my improved barrel-cover, showing the same attached to a barrel, the lower portion of the barrel being broken away. Fig. 2 is an inverted plan view showing the barrel in cross-section, and Fig. 3 is a sectional elevation taken on the line $\alpha\alpha$ of Fig. 1.

In the practice of my invention I provide primarily a circular cover A, comprising the two parts a and a' , the part a' being of an area considerably less than the part a to permit of ready access to the barrel when the lid is open. These two said parts are connected to each other by means of hinges a^2 , and they comprise, respectively, sections a^3 and a^4 , connected by means of dowels a^5 and a^6 . Around the periphery of the cover I form an annular groove a^7 , which provides the respective parts a and a' , with channels to receive retaining-wires 2 and 3, the respective ends of which are wound around nails or similar projections 4 and 5, driven into the two inner sections of the cover parts, whereby rigidity is supplied

to the said parts to prevent displacement of the several sections forming part thereof.

To connect the device to a barrel, a clamping device B is supplied and connected to the under surface of the section a' by means of the hanger C. This said clamping device comprises a series of prongs D, engaging hangers d and pivotally attached at their inner ends to an oscillating arm E, which is pivotally attached to the hanger C by means of the spindle c. This said arm E has a lever E' extended at an angle from one end thereof for the purpose of throwing the arm E, as illustrated by Fig. 2 of the drawings. Thus when the arm is placed in horizontal position or parallel with the inner edge of the section a' of the cover the prongs D are forced outwardly to the fullest extent, permitting their sharp ends to penetrate the inner wall of the barrel 1, as illustrated by dotted lines, Fig. 2, of the drawings, whereby the device is securely fastened to the barrel and the portion thereof occupied by the section a is in an open condition to admit of ready access to the barrel when the said section a is opened upon its hinges. When removing the device from the barrel, the clamp is thrown into the position illustrated by full lines, Fig. 2 of the drawings, thus releasing the prongs from the barrel-staves and allowing the device to be readily removed for the purpose of attaching it to another barrel, if desired, and the device is placed in this said position normally before it is attached to the barrel.

The section a' is preferably supplied upon its upper surface with a receptacle A', said receptacle comprising a segmental wall A², a vertical or approximately vertical wall A³, and a hinged lid A⁴, the wall A³ being supplied with a transparent window A⁵, adapted to exhibit the contents of the receptacle.

In the operation and use of the device after the barrel-head is removed the lid is attached thereto, as illustrated in the drawings. A portion of the contents of the barrel is then placed in the receptacle A' for the purpose of allowing the dealer to readily see what the body of the barrel contains. Then the lid may be maintained in a normally-closed condition, as illustrated in Fig. 1 of the drawings, and the dealer can exhibit the contents of the

barrel through the medium of the glass plate A⁵ without the necessity of exposing the said contents to the action of the atmosphere or to liability of receiving extraneous matter, such as dust, &c.

Having thus described my invention, what I claim as new, and desire to secure by Letters Patent, is—

1. In a barrel-closing device, the combination of a cover comprising a plate divided into two parts or sections hinged together, and a clamping device, secured to the under side of one of said sections and adapted to engage the interior of the barrel, said clamping device consisting of a hanger secured to said section, an oscillating lever pivoted in one end of said hanger, a pointed arm pivoted in one end of said lever, two similar pointed arms both having the same pivot connected to said lever at the same point, and guides secured to the under side of the section to guide the pointed arms and hold them in place.
2. In a barrel-cover, the combination of a sectional plate; a clamping device secured to the under side of one section thereof and consisting of a hanger secured to said section, an oscillating lever pivoted in one end of said hanger, a pointed arm pivoted in one end of said lever, two similar pointed arms both having the same pivot connected to said lever, and guides secured to the under side of

the section to guide the pointed arms and hold them in place; and an exhibiting-compartment secured to the upper surface of said section and provided with a hinged lid and a transparent wall to exhibit the contents.

3. In a barrel-closing device, the combination of a plate divided into two sections, which are composed of sections held together by dowels and peripherally-attached wires, one section being of a larger area than the other, the said sections being hinged together, and a clamping device secured to the under side of the smaller section to engage the interior of the barrel, said clamping device consisting of a hanger secured to said section, an oscillating lever pivoted in one end of said hanger, a pointed arm pivoted in one end of said lever, two similar pointed arms both having the same pivot connected to said lever, and guides secured to the under side of the section to guide their respective pointed arms and hold them in place.

In testimony that I claim the foregoing as my invention I have signed my name, in presence of two witnesses, this 4th day of October, 1898.

JOHN M. HOLMES.
